UNITED STATES PATENT OFFICE.

GEORGE B. CRAMP, OF DULUTH, MINNESOTA, ASSIGNOR TO MORGAN CONSTRUCTION COMPANY, OF WORCESTER, MASSACHUSETTS, A CORPORATION OF MASSACHUSETTS.

GAS-PRODUCER.

1,198,010.

Specification of Letters Patent. Patented Sept. 12, 1916.

Application filed January 10, 1914. Serial No. 811,460.

To all whom it may concern:

Be it known that I, GEORGE B. CRAMP, a citizen of the United States, residing at Duluth, in the county of St. Louis and State of Minnesota, have invented a new and useful Improvement in Gas-Producers, of which the following description, taken in connection with the accompanying drawings, is a specification.

- 10 The present invention relates to that class of gas producers in which there is provided beneath the body portion of the producer a rotatable ash support, comprising a relatively shallow pan having a flaring side. 15 Within said ash support and resting on the bottom thereof is a radial arm or scraper bar, journaled concentrically with the said ash support, which scraper bar, when held stationary with respect to the rotating ash support, causes the ashes to be crowded over the edge of the flaring side of said support and delivered therefrom.

20 The object of the present invention is to provide means for engaging said scraper bar to prevent its rotation, and for releasing the same to permit of its rotation with the ash support for a predetermined period, whereby the discharge of ashes from the ash support may be periodically interrupted and 25 readily governed.

A further object is to make such engaging and releasing means entirely automatic in operation, thereby doing away with the necessity of an attendant.

30 A further object is to make the operation of such engaging and releasing means adjustable, in order to permit the rotation of the scraper bar at varying intervals of time with respect to the constant rotation of the ash support, whereby a greater or less discharge of ashes can be effected in a given 35 period of time.

These objects, and others as will herein-after appear, are attained by means of the construction and arrangement of parts as hereinafter described and set forth in the appended claims.

40 Referring to the accompanying drawings: Figure 1 is a front elevation of a gas producer, of the class described, with parts broken away, to more clearly show the operating mechanism for the scraper bar. Fig. 55 45 50 55 60 65 70 75 80 85 90 95 100 105 110

of the latter. Fig. 3 is a sectional view on line 3—3, Fig. 2, of a portion of the gas producer, showing in side elevation the apparatus for controlling the operation of the scraper bar.

Similar reference characters refer to similar parts in the different views.

Referring to the drawings, 1 denotes the body portion of a gas producer, inclosing a heating chamber, and spaced above a rotatable ash support 2, consisting in the present instance of a relatively shallow pan, into which ashes are delivered from the said body portion through its open bottom. The ash support 2 is mounted upon friction rollers 3, 3 and is rotated by means of a rotating pinion 4 engaging an annular rack 5 upon the ash support.

60 65 70 75 80 85 90 95 100 105 110 Journaled concentrically with the rotating ash support 2 is a scraper bar 6, resting on the bottom of said ash support, and consisting, in the present instance, of a helically curved arm having its outer end 7 arranged to be engaged by a latch 8, the operation of which will be hereinafter described.

Journaled in bearings 9, 9 carried upon one side of a column 10 supporting the stationary body 1 of the producer is a shaft 11, having secured thereto at its inner end adjacent the ash support a star wheel 12, the arms of which are engaged by lugs 13, riveted to the wall of the ash support and serving to rotate the shaft 11 in predetermined relation to the rotation of the ash support, in the present instance, five or six times as fast. At the other side of said support, above the bearings 9, is a bearing 14, in alinement with a bearing 15 carried by the stationary body portion 1 of the producer, and in the said bearings 14 and 15 is journaled a shaft 16. Keyed to said shaft adjacent its outer end is a ratchet wheel 17, and on either side of said wheel, mounted to turn freely on said shaft are the depending members 18 and 19, connected together at their free ends, beyond the periphery of the wheel 17, by a pin 20 on which is pivotally mounted a pawl 21, for engaging the teeth of the ratchet wheel.

The outer member 18 is provided with a guideway 22 in which slides a cross head 23. At its outer end the shaft 11 is provided with an offset crank arm 24 to which is connected one end of a connecting rod 25, the other end thereof being pivotally connected to the sliding cross head 23. The

connecting rod, by the rotation of the shaft 11 and its crank arm 24, oscillates, by its connection with the cross head 23, the members 18 and 19 about the shaft 16 as a center, 5 and the degree of oscillation made by the pawl 21 on the lower ends of said members, depends upon the distance of said cross head from the center of shaft 16. The adjustment of said cross head, whereby a greater 10 or less degree of oscillation is afforded the pawl 21, is accomplished by means of a rod 26, pivotally connected to said cross head at one end, and having at its other end a handle 27, projecting above the operating floor and 15 provided with a series of notches 28, adapted to engage a fixed pin 29, whereby the rod is held in any desired position. The adjustment of the cross head causes the pawl 21 to make a swing of greater or less degree, 20 whereby the speed of rotation of the shaft 16 is varied. The said wheel 17 is prevented from turning in the reverse direction by means of an oppositely engaging pawl 30, pivotally mounted on the fixed column 10. 25 At its inner end, adjacent the bearing 15, the shaft 16 has a cam 31 keyed thereto, which cam is in the form of a circular disk having a notch 32 in its periphery. Pivotally mounted on the body portion 1 of the 30 producer is a lever 33, the short arm of which is provided with a roller 34 engaging the periphery of cam 31, while the end of its longer arm engages against the upper end of a rod 35, slideable in guides 36 and 35 37 carried by the body portion 1.

The latch 8, heretofore referred to, takes the form of a bell crank lever, freely pivoted on a bracket 38 depending from the stationary body portion 1, and having one arm normally interposed in the path of the free end of the scraper bar 6. The other arm of the latch carries a forwardly projecting pin 39, disposed in the path of the forked end 40 of the sliding rod 35. When the roller 34 is 40 engaged by the outer edge of the rotating cam 31, the forked end of the rod 35 is depressed, thereby retaining the latch in position to prevent rotation of the scraper bar 6. When, however, the notch 32 of the cam 45 comes under the roller 34, the pressure of the scraper bar 6 against the latch will force the rod 35 upwardly, thereby causing the roller to drop into the notch, and the scraper bar will pass under the latch and be carried 50 around through one revolution by the ash support. When the scraper bar again approaches the latch 8, the roller 34 will by then have passed out of notch 32, thereby depressing rod 35, to cause its forked end 55 to retain the latch in position to interrupt the rotation of the scraper bar, until the notch 32 again comes under roller 34. The proportion of the time during which the scraper bar is held stationary is determined 60 by the relative speed of rotation of the cam 65

31 and the ash support 2. For instance, in the cam makes one revolution during one and one-tenth revolutions of the ash support, the scraper bar will be held stationary during approximately one-tenth of each 70 revolution of the ash support. By the adjustment of rod 26 carrying cross head 23, the speed of rotation of cam 31 may be varied, thereby varying the time during which the scraper bar is held stationary. 75 It is also evident that more than one notch 32 may be provided in the periphery of the cam 31, so that by varying the number of notches and also the speed of the cam, practically any desired combinations of time for 80 alternately stopping and starting the movement of the scraper bar can be effected.

I claim,

1. In a gas producer, a rotating ash support, and automatic means for delivering 85 ashes therefrom at predetermined intervals in the rotation of said support.

2. In a gas producer, a rotating ash support, and automatically operated means co-operating with said support for continuously 90 delivering ashes from said support.

3. In a gas producer, a rotating ash support, means co-operating therewith to deliver ashes therefrom, and means actuated by said rotating support for periodically rendering 95 said co-operating means inactive.

4. In a gas producer, an ash support, automatic means for delivering ashes therefrom at predetermined intervals, and means for varying the periods of action of said 100 delivering means.

5. In a gas producer, a rotating ash support, means actuated by the rotation of said support for delivering ashes therefrom at 105 predetermined intervals in the rotation of said support, and means for varying the duration of said intervals.

6. In a gas producer, a rotating ash support, means co-operating therewith to deliver ashes therefrom, automatic means for 110 interrupting the action of said co-operating means, and automatic means for discontinuing the action of said interrupting means.

7. In a gas producer, a rotating ash support, means co-operating therewith to deliver 115 ashes therefrom and means actuated by the rotation of said support for periodically interrupting the action of said co-operating means.

8. In a gas producer, a rotating ash support, a scraper bar, adapted to be held stationary with respect to said ash support, and automatic means for permitting the rotation of said scraper bar with said ash support for predetermined periods in the 120 rotation of said support.

9. In a gas producer, a rotating ash support, a scraper bar, adapted to be held stationary with respect to said ash support, automatic means for permitting the rota- 125

tion of said scraper bar with said ash support for predetermined periods in the rotation of said support, and means for varying the duration of said periods.

5 10. In a gas producer, a rotating ash support, a scraper bar carried thereby, means normally held in the path of said scraper bar to prevent its rotation with said ash support, and automatic means for releasing said last 10 mentioned means periodically in the rotation of said support.

11. In a gas producer, a rotating ash support, a scraper bar carried thereby, a latch in the path of said scraper bar, means actuated by the rotation of said support for retaining said latch in engagement with said scraper bar, and automatic means for releasing said latch at predetermined intervals.

20 12. In a gas producer, a rotating ash support, a scraper bar carried thereby, a latch interposed in the path of said scraper bar, and automatic means for positively holding said latch in its operative position at predetermined intervals.

25 13. In a gas producer, a rotating ash support, a scraper bar carried thereby, a latch interposed in the path of said scraper bar, and automatic means for alternately engaging and disengaging said latch, to prevent 30

the rotation of said scraper bar at predetermined intervals.

14. In a gas producer, a rotating ash support, a scraper bar carried thereby and journaled on an axis concentric with said support, and means actuated by the rotation of said ash support for positively holding the scraper bar from rotation with said support at predetermined periods in the rotation of said support. 35

15. In a gas producer, a rotating ash support, and automatic means actuated by the rotation of said support for inaugurating the delivery of ashes therefrom at predetermined intervals. 40

16. In a gas producer, a rotating ash support, a scraper bar carried thereby and in frictional engagement therewith, a latch depending in the path of said scraper bar, and automatic means for intermittently holding said latch in said path, whereby the scraper bar effects the delivery of ashes from the support at regular intervals in the rotation of said support. 45 50

Dated this twenty-sixth day of December, 55
1913.
